VACUUM TUBE KEYING OF RESISTANCE COUPLING AMPLIFIER

Clarence B. Coleman, Baltimore, Md., assignor to Westinghouse Electric Corporation, East Pittsburgh, Pa., a corporation of Pennsylvania

Application May 20, 1950, Serial No. 163,294

9 Claims. (Cl. 250—27)

1

My invention relates to electric discharge apparatus and it has particular relation to electronic keyers.

The Usselman Patent 2,153,656 is illustrative of keyers of the prior art of which I am aware. Such keyers include one or more pentodes. Oscillations derived from an exciter are impressed between the control grids and the cathodes, and keying potential is impressed between the suppressor grids and the cathodes of the pentodes. The anodes of the pentodes are coupled to the control grids of following amplifiers. As the keying potential is varied, the pentodes pass from substantially conductive to a substantially non-conductive condition. During the intervals when the pentodes are conductive, trains of oscillations derived from the exciter are impressed on the following amplifiers. The variations in the pentode conductivity are thus impressed as modulations on oscillations derived from the exciter source. The signals transmitted when the pentodes are non-conductive may be designated as mark signals and the signals transmitted when the pentodes are conductive may be designated as gap signals. To achieve precision in signalling, it is essential that the mark and gap intervals be sharply defined; it is desirable then, that the trains of oscillations be initiated and terminated abruptly.

I have found that prior art keyers have the serious disadvantage that the mark-gap modulations are not sharply defined. The transmitted signal appears to pass gradually between the gap magnitude to the mark magnitude.

It is, accordingly, an object of my invention to provide a keyer which shall produce sharply defined mark-gap signals.

A more specific object of my invention is to provide a keyer capacitively coupled to following amplifying stages which shall produce sharply defined mark-gap signals.

An auxiliary object of my invention is to provide a novel pentode circuit.

My invention arises from the realization that the bluntness in the mark-gap signals is caused by the lag in the reference to the keying variations of the coupling network between the keyed pentode and the amplifiers. This network may include a coupling capacitor which is charged and discharged as the conductivity of the keyed pentode is varied by the keying oscillations. When the keyed pentode is substantially non-conductive, its anode and therefore one plate of the coupling capacitor are substantially at the positive potential of the supply. The coupling

2

capacitor is, therefore, charged to the potential of the supply. When the keyed pentode becomes conductive, the potential of the above-specified plate of the coupling capacitor is substantially reduced and the capacitor tends to discharge. As the keying potential is varied, the D. C. potential from the plate supply impressed on the capacitor thus varies in rhythm with the keying variation. In effect, then the oscillations from the exciter are modulated, not by a potential having the precise wave form of the keying potential, but by one having the wave form produced by the charge and discharge of the capacitor. The sharpness of this modulation is materially limited by the time required for the capacitor to discharge. This time interval is, in turn, dependent on the resistance in the discharging circuit of the capacitor and since this resistance is substantial, the rise and drop of the grid potential of the following amplifier is relatively gradual and the mark and gap signals are not sharply defined as is desirable.

In accordance with specific objects of my invention, I provide a pair of pentodes on the suppressor grids of which the keying signal is impressed and the screen grid of each of which is connected to the anode of the other. The anode of one of the keyer tubes is capacitatively coupled to the grid of the following amplifier. It is a property of a pentode that as the suppressor grid potential is varied, the total current drawn from the cathode by the screen grid and the anode remains constant. The variation in one sense of the current flowing to the anode is compensated by corresponding variations in the opposite sense of current flowing to the screen grid. As the current flow to the anode coupled to the amplifier varies, by reason of the keying variations, the current flow to the screen grid of the other tube varies in such manner as to compensate for the former variations. The charge on the coupling capacitor, therefore, remains substantially constant and the conductivity of the amplifier to which the keyer is coupled is varied sharply. The mark-gap modulations are, therefore, sharply distinguishable.

The novel features that I consider characteristic of my invention are set forth with particularity in the appended claims. The invention itself, however, both as to its organization and its method of operation, together with additional objects and advantages thereof will be understood from the following description of a specific embodiment when read in connection with the accompanying drawing in which the single figure

is a circuit diagram of a preferred embodiment of my invention.

The apparatus shown in the drawing includes a first pentode 1 having an anode 3, a cathode 5, a control grid 7, a screen grid 9 and a suppressor grid 11; and a second pentode 13 having similar electrodes 15, 17, 19, 21 and 23 respectively. The anodes are supplied from a suitable B supply (not shown) through load resistors 24 and 25. The cathodes 5 and 17 are grounded through cathode resistors 26 and 27 respectively and by-passed by by-pass capacitors 29 and 31 respectively of suitable magnitude. The output of an oscillator 33 preferably of the CW type is impressed between the control grid 7, and the cathode 5 of the first pentode 1 through a grid resistor 35. The suppressor grids 11 and 23 respectively, are connected together to the output of a keyer 37. The screen grid 9 and 21 of each pentode 1 and 13 respectively is connected directly or through a connection having substantially no impedance to the anode 15 and 3 of the other.

The keyer 37 may be of any well known type. In the preferred practice of my invention, it supplies alternatively negative potentials of such magnitude that when they are impressed on the suppressor grids 11 and 23 the pentodes 1 and 13 are non-conductive and positive potentials of such magnitude that when they are impressed on the suppressor grids, the pentodes 1 and 13 are substantially conductive.

The anode 3 of the first pentode 1 is coupled through a capacitor 39 to the control grid 41 of a following amplifier 43. The latter grid 41 may be grounded through a grid resistor 45. The output of the amplifier 43 may be coupled through frequency multipliers and output amplifiers 47 which may be, in turn, coupled to an antenna 49 of a communication line.

I have found that as a potential is supplied by the keyer, a signal having sharp mark and gap modulations is transmitted. When the keyer potential is negative, the anode current of both pentodes 1 and 13 is substantially zero. However, the screen grid 21 of the second pentode 13 draws current substantially equal to the current drawn by the anode 15 of this pentode (and therefore, by the anode 3 of the pentode 1) when it is fully conductive and, therefore, the direct current drawn from the B supply remains unchanged. While the first pentode 1 is non-conductive, the carrier oscillations impressed on its control grid are not transmitted through the coupling capacitor, therefore, these oscillations are not transmitted through the amplifier to the antenna.

When the potential derived from the keyer 37 is positive or at such other magnitude as to render the first pentode 1 conductive, the D. C. current drawn from the supply remains unchanged. However, the oscillations impressed from the oscillator 33 are now impressed through the coupling capacitor 39 on the amplifier 43 and transmitted by the antenna 49.

In the practice of my invention, the coupling capacitor 39 may also be connected to the anode of the second pentode 13. Under such circumstances, the carrier oscillations derived from the control grid 7 of the first pentode 1 are impressed through the screen grid 9 on the amplifier 43 when the second pentode 13 is non-conductive. The signal transmitted is then in opposite phase with reference to the keying variations to the signal which is transmitted with the coupling capacitor 39 connected with the anode 3 of the first

In a system in accordance with my invention which I have found to operate satisfactorily, the following components are included:

First pentode 1	GAU6
Second pentode 13	GAU6
Load resistor 24 of first pentode 1	51,000 ohm
Load resistor 25 of second pentode 13	51,000 ohm
Cathode resistor 26 of first pentode	1,200 ohm
Cathode resistor 27 of second pentode	1,200 ohm
By-pass capacitor 28 of first pentode	0.1 mf.
By-pass capacitor 31 of second pentode	0.1 mf.
Grid resistor 35 of first pentode	51,000 ohm
Coupling capacitor 39	0.1 mf.
Grid resistor 45 of amplifier 43	100,000 ohm
B potential	250 volt
Keyer output potential	25 volt
Oscillator (33) frequency	1 kc. to 100 kc.
Oscillator (33) potential	1 volt R. M. S.

While in accordance with the specific aspects of my invention a pair of pentodes 1 and 13 are included in the keying system, occasions may arise in which tubes of other types are applicable. For example, the pentodes may be included in a single envelope or a pair of pentagrid converters properly connected may have the properties necessary in the practice of my invention and may be utilized. Under certain circumstances the capacitive coupling 39 may be replaced by an inductive coupling; a coupling transformer, for example. To the extent that the basic concepts of my invention are applied to such an inductively coupled system, such system lies within the scope of my invention. Under certain circumstances the keyer and control potentials may be distributed differently among the grids of the pentodes than in the specific system illustrated. Such different distribution lies within the scope of the broad aspects of my invention.

My invention is herein shown as applied to the keying of radio frequency oscillations. It is also applicable to the keying of audio frequency oscillations. For example, the keyer in accordance with my invention may be connected to key the modulator of a transmitter operating by transmitting AM or FM modulated continuous waves.

While I have shown and described a specific embodiment of my invention, many modifications thereof are possible. My invention, therefore, is not to be restricted except insofar as is necessitated by the prior art and by the spirit of the appended claims.

I claim as my invention:

1. A keying circuit including a pair of pentodes and a network for impressing keying potentials simultaneously on the suppressor grids of said pentodes characterized by the fact that the screen grid of each of said pentodes is connected to the anode of the other of said pentodes through a connection having substantially no impedance.

2. In combination, a first electric discharge path defined by an anode and a cathode and including a control grid, a screen grid and a suppressor grid; connections for impressing a signal on said control grid; a second electric discharge path defined by an anode and a cathode and also including a control grid, a screen grid and a suppressor grid; a connection between said last-named control grid and cathode; a keying network; connections for impressing the output of said keying network on both said suppressor grids; a connection between the screen grid of each of said paths and the anode of the other of said paths; and an output connection including a coupling capacitor connected to the anode of one of said paths.

3. In combination, a first electric discharge path defined by an anode and a cathode and in-

cluding a control grid, a screen grid and a suppressor grid; a second electric discharge path defined by an anode and a cathode and also including a control grid, a screen grid and a suppressor grid; a keying network; connections for impressing the output of said keying network on said suppressor grids; a connection between the screen grid of each of said paths and the anode of the other of said paths; and an output connection including a coupling capacitor connected to the anode of one of said paths.

4. In combination, a first electric discharge path defined by an anode and a cathode and including a control grid, a screen grid and a suppressor grid; a second electric discharge path defined by an anode and a cathode and also including a control grid, a screen grid and a suppressor grid; a network for impressing control potentials on said suppressor grids; a connection between the screen grid of each of said paths and the anode of the other of said paths; and an output connection including a coupling capacitor connected to the anode of one of said paths.

5. In combination, a first electric discharge path defined by an anode and a cathode and including a control grid, a screen grid and a suppressor grid; a second electric discharge path defined by an anode and a cathode and also including a control grid, a screen grid and a suppressor grid; a connection of substantially no impedance between the screen grid of each of said paths and the anode of the other of said paths; and an output connection connected to the anode of one of said paths.

6. In combination, a first electric discharge path defined by an anode and a cathode and including a control grid, a screen grid and a suppressor grid; connections for impressing a signal on said control grid; a second electric discharge path defined by an anode and a cathode and also including a control grid, a screen grid and a suppressor grid; a connection between said last-named control grid and cathode; a keying network adapted to supply as an output alternatively a first potential which when impressed on the suppressor grid of either of said paths is sufficient to reduce the conductivity of said path to a low magnitude or a second potential which when impressed on the suppressor grid of either of said paths is sufficient to render said path substantially conductive; connections for impressing the output of said keying network on both said suppressor grids; a connection between the screen grid of each of said paths and the

anode of the other of said paths; and an output connection including a coupling capacitor connected to the anode of one of said paths.

7. In combination, a first electric discharge path defined by an anode and a cathode and including a control grid, a screen grid and a suppressor grid; a second electric discharge path defined by an anode and a cathode and also including a control grid, a screen grid and a suppressor grid; connections between said control grids and their associated cathodes, respectively; a keying network; connections for impressing the output of said keying network on said suppressor grids, a connection between the screen grid of each of said paths and the anode of the other of said paths; and an output connection including a coupling capacitor connected to the anode of one of said paths.

8. In combination, a first electric discharge path defined by an anode and a cathode and including a control grid, a screen grid and a suppressor grid; a second electric discharge path defined by an anode and a cathode and also including a control grid, a screen grid and a suppressor grid; connections between said control grids and their associated cathodes respectively; a connection between the screen grid of each of said paths and the anode of the other of said paths; and an output connection connected to the anode of one of said paths.

9. In combination, a first electric discharge path defined by an anode and a cathode and having a plurality of grids; a second discharge path defined by an anode and a cathode and also having a plurality of grids; a keyer; connections for impressing the output of said keyer on corresponding first grids of each of said paths; connections for impressing a signal on a second grid of said first path; connections between a second grid of said second path corresponding to said second grid of said first path and said cathode of said second path and a connection between a third grid of each path and the anode of the other path.
